UNITED STATES PATENT OFFICE.

THOMAS H. DODGE, OF WORCESTER, MASSACHUSETTS.

IMPROVEMENT IN STEAM AND AIR VALVES.

Specification forming part of Letters Patent No. 122,446, dated January 2, 1872.

To all whom it may concern:

Be it known that I, THOMAS H. DODGE, of the city and county of Worcester and Commonwealth of Massachusetts, have invented certain new and useful Improvements in Steam and Air Valves for Steam-Radiators, and for other purposes; and I do hereby declare the following to be a full, clear, and exact description of the same, reference being had to the accompanying drawing which forms a part of this specification, and in which—

Figure 1 represents a side view of my improved steam and air valve. Fig. 2 represents a front view of the same. Fig. 3 represents a longitudinal central section on line A B, Fig. 2; and Fig. 4 represents a transverse section on line C D, Fig. 1.

The nature of my invention consists in certain improvements in steam and air-valves, as will be hereafter explained.

The use of steam for heating buildings by means of radiators arranged in rooms is becoming quite general, especially in the larger towns and cities, and it is customary to furnish each radiator with a small valve or cock, whereby the steam can be tested, and by means of which any air confined within the radiators can be allowed to escape when the steam is turned on. I have found by experience and by general complaint that the valves in ordinary use are defective and their operation unsatisfactory, inasmuch as they are liable to be left open by persons when there is no steam in the radiators, and should steam then be let on while the valves are thus open the condensed steam and water escapes through the open valve, thereby occasioning more or less injury to floors, carpets, furniture, and other articles within the rooms.

The object of my present invention is to produce a valve for use upon steam-radiators which shall be more efficient and satisfactory in its operation, and which can, at the same time, be constructed cheaply, while it is convenient and durable.

It consists of a shell or body, marked A in the drawing, provided with a screw-stem, B, for securing it to the radiator, and with a suitable escape-nozzle, C. A flange, D, is formed upon the neck A', while a suitable screw-thread is formed on the interior of the body to receive the thread of the spindle E. A hollow rosette,

E', is formed upon the outer end of the spindle E, and within said rosette is arranged a volute spring, F, one end of which is secured to the neck A' of the body A, and the other end to the rim of the rosette E', in this instance by hooking its end into a recess, a, formed in the inner surface of the rim. The flange D serves to keep the spring F in place and protects it from injury. The end of the spring which is secured to the neck A' is, in this instance, attached by passing it through a slot cut in a lug, c, at one side of the neck for its reception, the extremity of the spring being turned up at an angle to prevent it from drawing out of the slot, as shown in Fig. 4. It will be understood that the ends of the spring may be attached to the neck and rosette-rim in any other manner, whereby a secure attachment is effected, as best suits the convenience of the manufacturer. The spring F, being arranged upon the outside of the valve-neck, is not liable to become injured by the steam and water which escapes when the valve is opened. If desired, a suitable stop device can be combined with the flange D to prevent the rosette E' from being turned back beyond a certain distance, and the spring thereby unduly strained by careless or incompetent persons.

In putting the valve together the spring is first secured in place on the neck A' and sufficiently coiled to be received within the rosette E'. The spindle E is then screwed in until its end strikes the valve-seat, after which a suitable tool is inserted through the space b between the flange D and rosette-rim into the hooked end of the spring, which latter is then drawn around until the desired tension is obtained, when the end of the spring is hooked into one of the recesses a on the rosette-rim, whereby the force of said spring is caused to act upon the spindle E through the rosette or head E', thus keeping the valve always closed, except when opened by power applied to the rosette E'.

When taking the valve apart it will be understood that the spring is first unhooked from the rosette and the operation reversed. By making the spindle E with a triple thread, a quarter revolution of the spindle will open the valve sufficiently for all practical purposes when in use, and the valve will instantly be closed by

the spring upon removing the counteracting power from the rosette.

I have tried this valve upon steam-radiators in my own building, and find it to be of great utility and value.

I am aware that volute springs have before been used to render valves and cocks self-closing, and this, therefore, I do not, broadly, claim. But by the arrangement of the flange or shield D with respect to the chambered rosette E' so that it shall be within the compass of the sides of the latter, leaving also a space, b, as above specified, all dust and dirt are effectually excluded from the interior of the chamber in which the spring is contained; and, at the same time, the tension of the spring may be adjusted by inserting a suitable instrument up through the space b, so as to engage with the hook on the outer end of the volute spring, and, by carrying

it around to engage with the one or the other of the notches a on the inside of the rosette, effect the adjusting of the tension of the spring without trouble.

What I claim, therefore, and desire to secure by Letters Patent, is—

The combination, with the valve-stem and chambered rosette, of the flange or shield D, of less diameter than said rosette, arranged within the compass of the sides of the same, so as to leave the annular opening b and the spring F placed within the chambered rosette, and connected with the same and the valve-neck or case, substantially as shown and set forth.

THOS. H. DODGE.
